WATTHOUR METER

Raymond A. Grosso, Troy, Mich., assignor to Sangamo
Electric Company, Springfield, Ill., a corporation of
Delaware

Filed Nov. 5, 1969, Ser. No. 19,959

Term of patent 14 years

Int. Cl. D10—10, 99

U.S. Cl. D52—6

FIG. 1 is a front perspective view of the watthour meter;

FIG. 2 is a rear plan view of the watthour meter;

FIG. 3 is a side elevation, looking in the direction of line 3—3 of FIG. 2; and

FIG. 4 is a top plan view, looking in the direction of line 4—4 of FIG. 3.

I claim:

The ornamental design for a watthour meter, as shown.
